UNITED STATES PATENT OFFICE.

FRANK S. FARNUM, OF BROCKTON, MASSACHUSETTS, ASSIGNOR TO CHURCHILL AND ALDEN COMPANY, OF BROCKTON, MASSACHUSETTS, A CORPORATION OF MASSACHUSETTS.

FOOTWEAR.

Application filed April 15, 1927. Serial No. 183,955.

This invention relates to shoes and similar articles of foot wear for persons of either sex or any age.

It is a well known fact that a large portion of the foot troubles now existent are the direct result of the defects in foot wear and the use of inappropriate types or styles thereof, made and assembled without due and proper regard for foot anatomy and 10 the requirements and necessary elements to prevent discomfort and foot disorders.

It is therefore the principal purpose of the present invention to produce a shoe in which a light weight but stiff and rigid 15 shank is used to support the human foot from ball to back, and at the same time permit the fore part of the foot to bend or flex naturally.

Further features of advantage and 20 standing novelty will be found in the construction of the shoe, one of which resides in the "over and over" sewing of the uppers together in a plane below the foot, that acts effectively as a support and prevents tearing 25 apart of the uppers, and the attachment of an outer sole by pegs in a manner to render the shank rigid and light.

These and other objects, which will become 30 apparent as the description proceeds, are accomplished by the novel construction and arrangement of parts hereinafter described and shown in the accompanying drawing, forming a material part of this disclosure, and in which:

35 Fig. 1 is a bottom plan view of a shoe made in accordance with the invention, the heel and part of the outer sole being removed.

Fig. 2 is a partial side elevational view of 40 the same parts being broken away to show the construction.

Fig. 3 is a bottom plan view of the rear part of the shoe showing the heel in position.

Fig. 4 is a partial transverse sectional view taken on line 4—4 of Fig. 3 and drawn to an enlarged scale.

In the accomplishment of this method of 50 shoe construction use is made of an ordinary wooden last 10, which may or may not be iron clad on its under surface to cause clinching of the lasting tacks.

On the last are assembled an inner sole 11, and upper 12, including the vamp 13 with

the toe cap 14 and welt 15, all of which parts are lasted in any usual manner.

As shown, the heel seat 16 of the shoe has been lasted by turning the lower edges of the upper inwardly, including the counter 17 and lining 18, these elements being held in place by lasting tacks 19.

At the heel seat the adjacent edges of the upper presents a generally ovoidal opening, as at 20, leading towards the front where a narrow space 21 is produced at the shank, thereafter opening outwardly between the 65 welt elements 15.

Extending rearwardly from the shank to the space 20, centrally of the shoe and juxtaposed on the outer surface of the inner sole 11 is a steel spring plate 22 covered by a 70 leather strip 23 secured in position by lasting tacks 24.

Either before or after the end portions of the shoe have been lasted, preferably after, the sides are lasted by drawing the edges of 75 the uppers inwardly towards each other along the space 21, over the strip 23 and passing a strong cord 25 from one side to the other in the manner of stitches, drawing the edges firmly towards the center of the shoe 80 by "over and over" sewing.

The cord may be used by threading it into the eye of a curved needle or other convenient method and both ends secured to prevent loosening of the stitches, which as will 85 be noted extend only under the shank of the shoe.

Thereafter an outer sole 26 is secured to the welt and vamp by any preferred stitching means, and is fastened to the shank by 90 wooden pegs 27 arranged in one or more rows, affording a firm rigid attaching means, light in weight and durable in use.

It is to be understood the pegs are driven through the outer sole, leather shank strip 95 and inner sole to become permanently retained, the inner points being removed, thus allowing the pegs to become firmly fastened, performing their full duty in holding the different parts together, positively preventing relative slipping of the upper, shank, insole and outsole, and rendering these elements unusually rigid.

The heel 28 is attached over the sole and heel seat in the usual manner, as indicated 105 by the securing means 29.

Although the foregoing is descriptive of the preferred embodiment of the invention, it will be apparent that minor changes may be made in its construction, without the exercise of invention or conflicting with the scope of the claims hereto appended.

I claim:

1. A shoe comprising an outer sole, an inner sole, a shank stiffener disposed on the inner sole, a pliable covering for said stiffener, said covering extending from the heel to the outer end of the arch of the shoe adjacent the sole, means for confining the lower edges of the shoe upper over said covering, and an outer sole thereover.

2. A shoe comprising an outer sole, an inner sole, a shank stiffener disposed on the inner sole, a pliable covering for said stiffener, said covering extending from the heel to the sole below the arch of the shoe, a cord for drawing and confining the lower edges of the shoe upper tightly against said covering, the ends of said cord being secured, an outer sole, and rows of wooden pegs driven through all of said elements at the shank portion of the shoe.

In testimony whereof I have hereunto affixed my signature.

FRANK S. FARNUM.
